to the United States of America

Application August 19, 1942, Serial No. 455,323

1 Claim. (Cl. 102—56)

1

This invention relates to projectiles such as grenades and more particularly to the type adapted to be projected from the ends of rifle barrels or the like and usually known as rifle grenades.

In the type of grenade hereunder consideration an explosive charge is carried in a suitable casing connected at one end to a tube arranged to fit over a rifle barrel or the like and to be projected therefrom by firing a blank cartridge in the rifle. The grenade charge may be exploded by a suitable firing mechanism actuated by impact of the grenade upon the target.

An object of this invention is to provide a projectile of this type constructed and arranged to embody a greater explosive power and destructive capacity for a given size of projectile than has heretofore been achieved, so far as we are aware.

A further object is to provide a rifle grenade of such design as to be capable of quantity production in large volume by conventional manufacturing operations.

A further object is to provide an armor piercing projectile of the grenade type constructed and arranged to have the maximum destructive effect upon the target.

These and other objects are attained by the invention hereinafter described in connection with the accompanying drawings in which:

Fig. 1 is a view partly in longitudinal section and partly in elevation of a rifle grenade constructed in accordance with one embodiment of this invention;

Fig. 2 is a view of a grenade similar to that shown in Fig. 1 but arranged for practice only, the explosive charge and firing mechanism being omitted;

Fig. 3 is a transverse sectional view on line 3—3 of Fig. 1;

Fig. 4 is a similar view on the line 4—4 of Fig. 1;

Figs. 5 and 6 are perspective views of the sheet metal casing and a collar member, respectively, prior to the assembly thereof;

Figs. 7 and 8 are sectional views thereof showing certain steps in the assembly thereof; and

Fig. 9 is a section on the line 9—9 of Fig. 8.

As illustrated in Figure 1, the present invention is shown in connection with a rifle grenade having a casing 10 formed by a sheet metal stamping for holding an explosive charge 11. The rear end of the casing is curved inwardly and provided with an opening 4 of polygonal outline, shown as hexagonal. A collar 3 having a roughened face 5 and a circular extension 6 is secured to the casing by locating the extension within the poly-

2

gonal opening with the roughened face 5 pressed against the end of the casing. In assembling, the extension 6 is spun outwardly to clamp the end of the casing against the roughened face 5. In the spinning operation the metal of the extension 6 expands into the corners of the hexagonal opening 4 and locks the collar and container against relative rotation. After the spinning operation, in order to eliminate any possible play between the parts, the material of the extension 6 which has been spun over against the rear face of the container is clinched at spaced intervals 7. After the assembling operation the collar 3 is provided with internal threads 8. A fuse assembly is provided including a body member 14 having an annular threaded projection 15 for engagement with the collar 3 and extending outwardly from the casing so as not to obstruct the interior thereof. The body member is provided with a closed-end bore 16 in which a firing pin 17 having a firing point 18 is slidably mounted and normally pressed against the closed end of the bore by a coil spring 19 located between the firing pin and a detonator cup 21 threaded in the open end of the bore. A booster charge 22 is also threaded in the outer end of the bore which is closed thereby.

A stabilizer assembly including a sheet metal tube 23 is secured to the outer reduced end 24 of the fuse assembly body member 14 by four sheet metal drive screws 25 and spot welds 25'. The outer end of the tube 23 is provided with a plurality of stabilizer fins 26 for stabilizing the projectile in flight. As illustrated, each fin is spot welded to the outer face of the tube and extends radially outward therefrom. Each fin is then bent to form a circumferential section 27 concentric with the tube 23 and extending circumferentially to the adjacent fin 26, being spot welded to a depression 28 formed therein. The resulting stabilizer surfaces include the radial fins and an outer, connecting, circumferential ring 29. As illustrated, three fins and circumferential sections complete the assembly.

The firing pin is normally locked against movement. The lock shown consists of a flexible safety or locking pin 31 extending through a hole 32 in the body member 14 and engaging in a groove 33 in the firing pin 17. The locking pin is flexible and is preferably bent so as to extend for a short distance longitudinally of the tube 23 and then circumferentially thereof a distance sufficient to snap around the stabilizer tube and thus be held resiliently in the position shown in full lines in Figs. 1 and 4. The end 34 of the safety pin preferably projects in the man-

ner shown so as to be easily seized. In this construction it will be noted that the safety pin forms an integral part of the fuse assembly and is entirely separated from the explosive charge.

In order to gain full advantage of the increased shattering effect produced by an explosive charge when the surface facing the target is concave in form, the present invention comprises a cone 35 of pressed sheet metal having a circumferential flange 36 at the base thereof engaging the forward end of the casing 10, the cone extending into the explosive charge for a distance, in the illustrated embodiment, slightly more than one-half the length of the casing, thus leaving a substantial column of explosive between the apex of the cone and the opposite end of the casing. The cone is also secured in position by an ogive 37, also of pressed sheet metal, which extends forwardly from the casing and which is secured thereto by having the end 38 spun into the groove 39 formed in the outer face of the casing adjacent the forward end thereof. The ogive is provided with a plurality of circumferentially spaced indentations 41 positioned so as to engage flange 36 of the cone and press it firmly into position against the end of the casing 10.

Fig. 2 illustrates the grenade of Fig. 1 modified for practice purposes without any explosive being present. In this construction an end plug 42 is threaded into the collar 12 and has a bar-shaped extension 43 which projects forwardly into the casing 10 a sufficient distance to provide the weight and balance characteristics of a loaded grenade. Also, the cone 35 is omitted and the ogive 37 is connected to the casing 10 in the manner described in connection with Fig. 1 but without the cone being interposed between the casing and the ogive.

In firing a grenade, the safety pin 31 is first untwisted by bending it into the dotted line position shown in Figs. 1 and 4, and then extracted to free the firing pin. The grenade is then placed over the end of a rifle barrel. Upon firing a blank cartridge in the rifle the grenade is propelled at high velocity against the target. Upon impact the ogive is crushed and the firing pin projected forwardly to explode the detonator 21 and booster charge 22, in turn exploding the charge 11 in the casing 10.

An important part of the present invention lies in the relative dimensions of certain parts. We have discovered that the relative length of the ogive has a direct bearing upon the effectiveness of the explosion of the charge 11. That is to say, the distance from the head or point of the ogive to the head of the body of the projectile, commonly spoken of as "the base of the cone," is critical. We have determined that for a fixed velocity of projectile and a certain brizance (rate of propagation of the explosive charge), a certain length of ogive is required for maximum destructive effect. This length should be such that the base of the cone is spaced from the surface of the target at the time of detonation. Obviously the time of firing is subject to control by the length of the ogive. Likewise, the destructive effect is increased by lengthening the column of explosive between the apex of the cone 35 and the opposite end of the casing 10, up to a cer-

tain maximum dimension of approximately eight inches. For example, with the proper dimensions the explosion will not only shatter armor plating, but will cause the cone 35 to penetrate such plating as a projectile.

By providing for rear end detonation, it will be apparent that the present construction will produce a straight line explosion wave traveling from the detonator through the booster charge and the explosive mixture, from the rear to the front.

The construction of parts is such as to permit quantity production and assembly at a high rate. Simple spinning and clinching operations are all that is required to secure the ogive and cone in place at one end of the casing and the collar 3 at the other. The stabilizer tube to which the fins 26 have been previously welded, is secured to the firing assembly body member by four driven fasteners and spot welds, and the two subassemblies are connected together by threading the body member into the collar 13. Obviously, the invention can be variously modified and adapted within the scope of the appended claim.

What is claimed is:

An explosive projectile comprising in combination an annular casing for holding an explosive charge, said casing having at least one open end and a peripheral recess in the external surface thereof adjacent said open end, a charge retaining cone within said open end and having a peripheral flange in engagement with the transverse face of said open end, and a sheet metal ogive surrounding said open end and having a circumferentially spaced series of radially inwardly offset portions, the offset portions of said series engaging said flange, said ogive having a peripheral flange in engagement with said peripheral recess, whereby said ogive retains said cone and said casing in fixed relation to each other and to itself.
